UNITED STATES PATENT OFFICE.

GEORGES LEQUEUX, OF PARIS, FRANCE.

HYDRAULIC APPARATUS FOR CLASSIFYING HETEROGENEOUS GRANULOUS MATERIALS.

Application filed March 19, 1924. Serial No. 700,328.

To all whom it may concern:

Be it known that I, GEORGES LEQUEUX, a citizen of the French Republic, residing at 63 Avenue des Champs Elysees, Paris, France, have invented new and useful Improvements in Hydraulic Apparatus for Classifying Heterogeneous Granulous Materials, of which the following is the specification.

The present invention relates to an improved hydraulic apparatus for classifying heterogeneous granulous materials and has for its primary object to improve the classification and to increase the output of the apparatus.

15 The accompanying drawing illustrates by way of example only and diagrammatically, a form of construction of the invention.

Fig. 1 is an elevation of the apparatus.

Fig. 2 is an elevation in partial section, 20 on enlarged scale, of the part of Fig. 1 designated by D.

Fig. 3 is an elevation with partial section, on enlarged scale, of the part of Fig. 1 designated by E.

25 Fig. 4 is an elevation with partial section, on enlarged scale, of the part of Fig. 1 designated by F.

Fig. 5 is a section on A—A of Fig. 3.

30 Fig. 6 is a section on B—B of Fig. 3.

Fig. 7 is a section on C—C of Fig. 4.

In this example, the raw materials to be separated are fed through the trough 1 and they are drawn in the trough 2 by means of a stream of water the intensity of which is 35 adjustable by the cock 3.

The trough 5 has a curved bottom (Fig. 2) and is slightly inclined on the horizontal. Under the influence of the stream of water, the materials are classified in horizontal layers by order of densities, the light materials being situated at the upper part of the bed, and the heavy materials at the lower part of the bed. At its lower end, the trough 2 is secured on an ascending water stream apparatus 5; this apparatus is essentially constituted by a trough 5^a connected to the trough 2 and in which open a series of vertical columns 5^b, 5^c, 5^d Figs. 2 and 6 communicating on the other hand at their lower part with the columns 5^e, 5^f, 5^g, through openings such as 5^h. Walls such as 5ⁱ close the lower part of the columns 5^e, 5^f, 5^g, whilst the columns 5^b, 5^c, 5^d, open in the cylindrical chamber 5^k in which rotates a distributor 5^l, actuated for instance by the pulley 5^m (Fig.

5). The cross section of this distributor is such that the columns 5^b, 5^c, 5^d, are never directly in relation with the atmosphere. The columns 5^e, 5^f, 5^g are connected to water inlet pipe-lines, such as 6, each provided with a cock 7, which permits to adjust the pressure of the water in each of the columns. Above the outlet point of the columns 5^b, 5^c, 5^d, in the trough 5^a is arranged a plate 5ⁿ, secured to the cross bar 5^v, against which 60 slides a damper 4. The plate 5ⁿ is perforated on a portion of its length in the shape of a sieve and under this perforated part is arranged another trough 5^p in communication with a water exhaust pipe line 5^q. 70

In order to make the damper 4 adjustable, the latter is pivoted at 4^a on a screw threaded rod 4^b, which passes through the bore of a support 4^c and is secured by means of nuts 4^d and 4^e. For raising the damper 4, it suffices to unscrew the nut 4^f and to screw the nut 4^d; reversely, for lowering the damper, it suffices to loosen the nut 4^f and to tighten the nut 4^d. 75

The materials arriving at the end of the trough 2 are separated in two by the damper 4; the upper layers (light materials) pass over the damper 4 on the plate 5ⁿ; the lower layers (heavy materials) pass under the damper 4. These materials, when arriving in front of the outlet point of the columns 5^e, 5^f, 5^g, would fall vertically in these columns, if they did not encounter the antagonistic vertical water stream. Owing to these currents, alone the materials of the greatest density can fall in these columns; the materials of lesser density are brought back by the vertical stream of water towards the orifice 5^r. The materials which fall to the bottom of the columns 5^e, 5^f, 5^g, are evacuated through the rotating distributor 5^l. For avoiding the wedging actions which might occur, paddles 5^s are rigidly secured on the axis 5^t which projects to the exterior and on which is rigidly secured an arm 5^u; a spring 5^v acts between this arm and a boss 5^x integral with the frame 5, in such a manner that the paddle 5^s may be always pressed against the distributor 5^l, but it is obvious that, when a stone wedges between this distributor 5^l and the paddle 5^s, the latter rotates for allowing the stone to escape. 95

The lighter materials pass on the plate 5ⁿ and water escapes, through the holes of the 100 105 110

perforated part into the trough 5^a and in the pipe line 5^a. This evacuation of water compensates the supplementary admission of water through the columns 5^b, 5^c, 5^d.

5 The arrangement of the plate 5^a above the outlet point of these columns 5^b, 5^c, 5^d, is considered as extremely important; in fact, this plate, prevents the destruction of the previous classification of the light materials

10 which pass on the plate 5^a. The arrangement of this plate allows to combine the classification by inclined troughs with the classification by ascending stream of water; if this plate (with of course, the damper 4) were omitted, the combination of these two methods of classification would be entirely inoperative because this ascending stream of water would destroy the previous classification effected by the inclined trough.

20 To the trough 5^a is connected a portion of the inclined trough 8, the end of which is partially closed by a partition 8^a. A damper 9 slides along this partition 8^a; it is pivoted at 9^a on a rod 9^b, which passes through a bore of a support 9^c secured on the trough 5^a. The screw threaded rod 9^b is immobilized by nuts 9^d and 9^e. It will be seen that this arrangement is quite similar to that of the damper 4. On the other hand, a plate 8^b forms an extension of the plate 5^a; the light materials having passed on this plate, and those which have been brought back by the vertical stream of water under the plate 8^b meet after this plate and pass under the damper 9 in the inclined trough 10 which is in the train of the trough 8. In this trough 10, as previously in the trough 2, is formed a bed of materials roughly classified by order of densities. In the train of the 30 trough 10 might therefore be arranged an apparatus similar to 5 (but the vertical streams of water would have pressures less high) for completing the classification, and so on; but a classification not sufficiently 40 precise of the materials would thus be obtained, which materials have, at the end of the treatment, densities somewhat near each other. It is then necessary to use a mechanical shaking classifying apparatus constituted in the following manner:

The trough 10 opens above a plate 11 acting as a sieve, constituted for instance by a wire gauze or a perforated sheet-iron plate. This plate forms the bottom of a box having three sides 11^a, 11^b, 11^c, (Figs. 4 and 7) the fourth side 11^d being open. On this side is arranged a plate acting as a dam 11^e, in front of which is an adjustable damper 12, quite similar to the dampers 4 and 9 and 50 which consequently, it is not necessary to describe any further. The sides 11^b and 11^c each carry trunnions 11^f and 11^g to which are pivotally connected the big ends of connecting rods 13 and 14. These connecting

55 rods are rigidly secured on shafts 15 and 16, supported by bearings such as 17, integral with the outer casing 18. This casing receives at its lower part a hopper 19, a branch 19^a of which is connected to an exhaust pipe line 20 through the medium of a valve 21. On the other hand, on the shafts 15 and 16, 70 are rigidly secured arms 22 and 23 supporting counterweights 24 and 25.

The side 11^a is provided with a fork piece 11^h on which is pivoted, by means of an axis 26, a connecting rod 27. On the other hand, a connecting rod 28 is pivotally connected through the axis 29 on a fork piece 30, which is secured on the wall 18^a of the casing. The two connecting rods 27 and 28 are pivotally connected together, through the axis 31, to a rod in two parts 32^a—32^b. The two parts 32^a—32^b are connected by a nut 32^c which allows, by screwing or unscrewing on the screw-threaded ends of the parts 32^a and 32^b, of adjusting the total length of the rod 32^a—32^b. The part 32^b terminates in a fork member 32^d, which receives an axis 33 an end of which is guided in a groove 18^b of the wall 18^a of a case 18^d secured to the casing 18. On the axis 33 is mounted a roller 34 which will come in contact with and bear against a cam 35 rigidly secured on the shaft 36; this shaft is caused to rotate through the pulley 37 and the belt 38 for instance. It is obvious that the rotation of the shaft 36 has for effect to impart shocks or vibrations to the plate 11, so as to produce the classification of the layer of materials by order of densities.

100 For facilitating this classification, streams of water are caused to enter through the radially perforated tubes 39 and 40, the admission in each of these tubes being controlled by a cock such as 41. The lightest materials are carried over the damper 12 and the plate 11^e and the denser materials pass under this plate. Of course, the very fine materials pass through the holes of the sieve; they are eliminated through the sluice-valve 21. In general, these fine materials are of great density; in the case of separation of coal, these fine materials are especially composed of pyrites.

110 In the train of the shaking classifying apparatus described, is arranged an ascending water stream separation apparatus, the constitution and method of separation of which are entirely identical to those described for the apparatus 5; it is the reason why it has not been considered necessary to repeat this description. In the drawing have been simply indicated for the ascending water stream apparatus not described the same numbers of reference as for the apparatuses 5 and 9, these numbers of reference being however provided with indicia. The very light materials which are not

eliminated are then evacuated through the final trough 39, the outflow being controlled by the damper 9'.

What I claim as my invention and desire 5 to secure by Letters Patent is:

1. In a hydraulic apparatus for classifying heterogeneous granulous materials, means for classifying the materials in approximately horizontal layers, according to 10 their densities, within an approximately horizontal channel through which passes a stream of water, a vertical conduit, through which passes an ascending stream of water and opening through an orifice in the said 15 channel, an approximately horizontal plate placed above the vertical conduit and completely covering the orifice of this conduit, the front and rear edges of the said plate being at a level higher than the bottom of 20 the channel.
2. In a hydraulic apparatus for classifying heterogeneous granulous materials, means for classifying the materials in approximately horizontal layers, according to 25 their densities, within an approximately horizontal channel through which passes a stream of water, a vertical conduit, through which passes an ascending stream of water and opening through an orifice in the said 30 channel, an approximately horizontal plate placed above the vertical conduit and com-

pletely covering the orifice of this conduit, the front and rear edges of the said plate being at a level higher than the bottom of 35 the channel, a damper arranged against the front edge of the said plate, means for adjusting the position of this damper.

3. In a hydraulic apparatus for classifying heterogeneous granulous materials, means for classifying the materials in approximately horizontal layers, according to 40 their densities, within an approximately horizontal channel through which passes a stream of water, a vertical conduit, through which passes an ascending stream of water 45 and opening through an orifice in the said channel, an approximately horizontal plate perforated on a portion of its length, placed above the vertical conduit and completely 50 covering the orifice of this conduit, the front and rear edges of the said plate being at a level higher than the bottom of the channel, a damper arranged against the front edge of the said plate, means for adjusting the position of this damper, a reservoir 55 arranged under the perforated portion of the plate and an exhaust pipe line opening in the said reservoir.

In testimony whereof I have signed my name to this specification.

GEORGES LEQUEUX.
